Des. 205,744
Patented Sept. 13, 1966

205,744

MEMORANDUM INDEX

Clayton A. Laughlin, Minneapolis, Minn., assignor to Standard Packaging Corporation, New York, N.Y., a corporation of Virginia

Filed Oct. 15, 1965, Ser. No. 87,498

Term of patent 14 years

(Cl. D74—1)

FIG.1

FIGURE 1 is a top plan view of a memorandum index showing my new design;

I claim:

The ornamental design for a memorandum index, as shown and described.
